COMBINED TOP AND BACKGUARD PANEL FOR COOKING RANGES

Chester C. Perry, Chagrin Falls, and Howard E. Brehm, Shaker Heights, Ohio, assignors to Perfection Stove Company, Cleveland, Ohio, a corporation of Ohio

Application September 14, 1950, Serial No. 12,184

Term of patent 14 years

(Cl. D81—25)

To all whom it may concern:

Be it known that we, Chester C. Perry and Howard E. Brehm, citizens of the United States, residing at Chagrin Falls and Shaker Heights, respectively, in the county of Cuyahoga and State of Ohio, have invented a new, original, and ornamental Design for a Combined Top and Backguard Panel for Cooking Ranges, of which the following is a specification, reference being had to the accompanying drawing, forming part hereof, wherein

Fig. 1 is a front elevational view of a combined top and backguard panel for cooking ranges embodying our new design;

Fig. 2 is a fragmentary side elevational view thereof; and

Fig. 3 is an enlarged sectional view taken on line 3—3 of Fig. 1 looking in the direction of the arrows.

The dominant features of the design reside in the portions shown in full lines in the drawing.

We claim:

The ornamental design for a combined top and backguard panel for cooking ranges, substantially as shown and described.

CHESTER C. PERRY.
HOWARD E. BREHM.
